ABRASIVE IMPLEMENT

Chalmers H. Randolph, St. Paul, Minn., assignor
to Minnesota Mining & Manufacturing Com-
pany, St. Paul, Minn., a corporation of Dela-
ware

Application April 7, 1944, Serial No. 529,973

12 Claims. (Cl. 51—170)

1

This invention relates to implements for employing sheeted abrasive material in abrading operations.

It finds particular utility in the form of implements suitable for using "abrasive tape" (which may be strips of the abrasive sheet material that is commonly called "sandpaper") in abrading irregular and/or small surfaces, or for various special abrading operations.

One objective is to provide an implement which will abrade efficiently with abrasive tape and which will itself hold a substantial supply of the tape in a manner to permit bringing fresh portions of tape into abrading position whenever the operator desires.

Another objective is to provide such an implement that is compact and otherwise suitable for abrading irregular and/or small surfaces, particularly when in places that are difficult of access with ordinary abrading devices.

Briefly, the present invention provides a device or implement comprising a body portion having a "backing" surface or "presser" surface adjacent to which abrasive tape may lie when the tape is in abrading position and which bears or presses against the back of the tape when the tape is being pressed or applied by the implement against an object (a workpiece) in an abrading operation, and a supply spindle and a take-up spindle rotatably mounted on or in the body, the said spindles being adapted to carry rolls of abrasive tape and being located in relation to each other and to the presser surface so that tape may be led from a supply roll thereof on the supply spindle to abrading position adjacent the presser surface and thence to the take-up spindle whereby fresh portions of tape may be brought into abrading position when desired.

The device described and illustrated herein as an illustrative embodiment of this invention is an elongated abrasive tool of a shape and design generally resembling that of a large screwdriver in which the flat sides of the outer tip portion or blade provide the presser or backing surfaces for applying the tape to a workpiece and the shank portion is hollowed out to form a magazine or chamber for holding a supply roll and from out of which the tape is led outwardly along one surface of the blade or "finger," thence around the outer tip thereof and thence back along the opposite side to a take-up roll in the magazine.

Figure 1 shows the described abrasive device in use.

Figure 2 is a top elevation or plan view of the finger and the magazine.

2

Figure 3 is a left side elevation of the finger and the magazine.

Figure 4 is a horizontal longitudinal sectional view of the finger and the magazine taken on the line 4—4 in Figure 3.

Figure 5 is a vertical cross-sectional view of the magazine taken axially of the forward spindle on the line 5—5 in Figure 3.

Figure 6 is a vertical longitudinal sectional view of the magazine taken on the line 6—6 in Figure 4.

Figure 7 is a vertical cross-sectional view of the forward portion of the magazine taken on the line 7—7 of Figure 3.

15 The body comprises generally the frame, housing, chamber or magazine 11 and the attached presser member, blade or finger 12. The finger portion of the body carries a padding layer 13 to provide the backing or presser surfaces 14 and 14' adjacent to which the abrasive tape T lies when in abrading position and which bear against the back of the tape when the tape is being pressed by the implement against an object or workpiece, such as the object 15, in an abrading operation.

20 A supply roll R of the tape is mounted or wound upon the supply spindle 16 from whence the tape is led out of the magazine 11 through the opening 17 adjacent a guide roll or shaft 18, thence along the backing surface or presser surface 14 of the finger 12, abrasive side out, thence around the outer end or tip of the finger, thence back along the presser surface 14', through the magazine opening 11' adjacent the guide shaft 30 18' and into the interior of the magazine where it is wound up on the take-up spindle 16' to form a roll R' of used tape.

25 The rolls are fixed to the spindles 16—16' in order that rotation of the spindles, which are 40 suitably journaled in the side wall 24 of the magazine, will wind or unwind the tape. Knurled wheels or thumb-turns 19—19' are fixed to the spindles 16—16', respectively, to provide means for turning the latter.

35 45 To provide braking means for holding the tape against motion during an abrading operation, two ratchet wheels 20—20' are fixed on the spindles 16—16', respectively, each wheel having radially extending V-shaped grooves or notches 50 21—21', respectively, near the periphery on its side surface facing the wall 24. The notches are adapted to receive the pawls 22—22', respectively, which latter are fixed on opposite ends of a leaf spring 23. The parts of the magazine are positioned so that there is a space between the

ratchet wheels 20—20' and the side wall 24 of the magazine 11 to accommodate the spring. The spring is suitably fixed at its approximate center to the side wall 24 and is sprung or loaded so that its extremities or ends which carry the pawls 22—22' are pressed against the ratchet wheels 20—20' so that whenever a wheel 20 or 20' turns so as to bring a notch 21 or 21' opposite a pawl 22 or 22', the pawl will enter and be held in the notch, thereby holding the ratchet wheel and its respective spindle 16 or 16' against turning in either direction. But since the notches are V-shaped in cross-section and the pawls are held yieldably by the spring 23, a turning impulse applied manually by the operator to the thumb-turn 19 in either direction, or to the thumb-turn 19' in either direction will unseat the pawl and the corresponding spindle will yield to the rotating impulse of the thumb-turn, thus providing a two-direction pawl and ratchet means which permits the spindles to be rotated in either direction.

The braking or holding power of the pawls and ratchets are preferably adjusted (by suitable means or design such as depth of notches, strength of spring, etc.) to be sufficient to hold the tape substantially motionless along the presser surfaces 14 and/or 14' during an abrading operation, yet not so great but what they will release the spindles 16—16' in response to a turning impulse applied manually by the operator to the thumb-turns 19 or 19' in either direction. Provision of a padding 13 on the finger 12 to form the tape-contacting presser surfaces 14—14', particularly when such padding is one or more layers of cloth or other rough surfaced material that make a good frictional contact with the tape backing, assists in holding the tape substantially motionless during an abrading operation.

The notches 21—21' may be spaced from each other by any suitable distance on the ratchet wheels 20—20', as long as they are close enough together so that a notch will be opposite a pawl when a spindle has turned to draw the tape to a desired degree of tautness along a presser surface. One means for accomplishing this with a minimum number of notches is to space the notches closer together on one wheel than on the other. In the illustrated embodiment the notches 21 on the ratchet wheel 20 are closer together than the notches 21' on the ratchet wheel 20' (Figure 6). After a length of fresh tape has been positioned along the presser surface 14 by first unwinding it from supply spindle 16 and next winding up the spent portion of tape on take-up spindle 16' until the slack is taken up, the spindle 16' may then be turned to the point of maximum tautness for the tape along the surface 14' at which the pawl 22' will engage a notch 21', whereupon the final tightening of the tape may then be accomplished by turning the spindle 16 to the point of maximum tautness for the tape along the surface 14 at which the pawl 22 will engage a notch 21.

It will be apparent that the closer the notches are together, the greater the degree of tautness to which the tape can be drawn and held by the spindle with which such notches are associated. Consequently, in the illustrated embodiment, the tape adjacent the presser surface 14 is usually more taut than that adjacent the surface 14', and the surface 14 is therefore usually the preferred backing or presser surface in the illustrated embodiment. However, it is to be under-

stood that surface 14' may also serve as a backing or presser surface; and that either spindle 16 or 16' may be the supply spindle (and the other the take-up spindle); and that either ratchet wheel 20 or 20', whether associated with the supply or the take-up spindle, may carry the closer spaced notches. The notches 21—21' need not necessarily be V-shaped in cross-section as long as they and the pawls 22—22' are shaped in relation to each other so that the pawls will be unseated and will release the ratchet wheels in response to a turning impulse that is manually applied to the thumb-turn 19 in either direction or to the thumb-turn 19' in either direction. If desired, a one-direction ratchet means may be used for a take-up spindle but, whatever braking means is employed, it is preferable that both spindles be rotatable in both directions whenever the operator so desires.

In use, the device may be equipped with a handle or handles suitably attached, as to the stud 25, and employed by applying the finger to an object to be abraded. The illustrated embodiment is shown equipped with a vibrator 26 that is powered through a cable 27. When fixed firmly to the stud 25 the vibrator causes the entire device, including the finger 12, to vibrate so that manual pressure by the operator of the finger (covered with the abrasive tape as above described) against a workpiece 15 causes the portion of the workpiece thus contacted to be abraded.

The device is thus seen to be particularly adapted to abrading small and relatively inaccessible surfaces, or to abrading small selected areas of large surfaces. An extremely small area can be abraded by application of only the tip end of the vibrating finger thereto.

The finger 12 may be of any suitable size, shape or design as long as it provides a presser surface over which abrasive tape may be drawn and held taut. Or the magazine 11 may itself be the "finger" with one or more surfaces serving as the presser surface. The word "tape" as used herein is a relative term, referring to sheets that are long in proportion to their width, and the principle disclosed herein may be employed to construct devices for using strips or lengths of abrasive sheet material of any width in a wide variety of abrading operations.

Various other alternatives will be obvious to those skilled in the art as usable for the carrying out of this invention without departure therefrom; also it is to be understood that the abrasive finger described and illustrated herein is simply illustrative of this invention, the scope of which is defined only by the claims.

I claim:

1. An elongate abrasive implement for the application of abrasive tape comprising an outwardly extending blade or finger which forms the forward portion of the implement, a handle which forms the rear portion of the implement, an intermediate shank portion hollowed out to form a supply magazine having suitable apertures through which the tape may enter and leave the magazine, the longitudinal axes of the finger, shank and handle being in approximate alignment, the finger having at least one backing surface adjacent to which abrasive tape may be laid to back the tape when the tape is being employed to abrade an object by application thereto of a tape-covered surface of the finger, two spindles rotatably mounted within the magazine, the said finger and spindles being located in re-

lation to each other, to the magazine and to the apertures therein in such manner that abrasive tape may be led from a supply roll thereof on one spindle, outwardly through one of the apertures, along one surface of the finger, around the end thereof, back along another surface of the finger, inwardly through another of the apertures into the magazine to the second spindle, means for rotating the spindles and a braking means associated with each spindle adapted to hold the spindles fixed against turning from the pull of the tape during abrading operations and to release them for rotation during operation of the rotating means.

2. The device of claim 1 in which each braking means comprises a pawl and ratchet.

3. The device of claim 1 in which each braking means comprises a pawl and ratchet means comprising a notched wheel fixed to the spindle, a pawl, and spring means for releasably holding the pawl in a notch, the notches on one ratchet wheel being in closer spaced relation to each other than are the notches on the other ratchet wheel.

4. An elongate abrasive implement for the application of abrasive tape comprising an outwardly extending blade or finger which forms the forward portion of the implement, a handle which forms the rear portion of the implement, an intermediate shank portion hollowed out to form a supply magazine having suitable apertures through which the tape may enter and leave the magazine, the longitudinal axes of the finger, shank and handle being in approximate alignment, the finger having at least one backing surface adjacent to which abrasive tape may be laid to back the tape when the tape is being employed to abrade an object by application thereto of a tape-covered surface of the finger, two spindles rotatably mounted within the magazine, the said finger and spindles being located in relation to each other, to the magazine and to the apertures therein in such manner that abrasive tape may be led from a supply roll thereof on one spindle, outwardly through one of the apertures, along one surface of the finger, around the end thereof, back along another surface of the finger, inwardly through another of the apertures into the magazine to the second spindle, means for rotating the spindles separately in either direction and a braking means associated with each spindle adapted to release them for rotation in either direction upon operation of the said rotating means and adapted to hold the spindles fixed against turning in either direction from the pull of the tape to hold the tape taut along the backing surface during an abrading operation.

5. The device of claim 4 in which each braking means comprises a two-direction ratchet.

6. The device of claim 4 in which each braking means comprises a two-directional pawl and ratchet means comprising a notched wheel fixed to the spindle, a pawl, and spring means for releasably holding the pawl in a notch, the pawl and notches being shaped and positioned to render the pawl's resistance to rotation of the wheel approximately equal in each direction.

7. The device of claim 4 in which each braking means comprises a two-directional pawl and ratchet means comprising a notched wheel fixed to the spindle, a pawl, and spring means for re-

leasably holding the pawl in a notch, the pawl and notches being shaped and positioned to render the pawl's resistance to rotation of the wheel approximately equal in each direction and the notches on one ratchet wheel being in closer spaced relation to each other than are the notches on the other ratchet wheel.

8. The device of claim 4 in which each braking means comprises a two-directional pawl and ratchet means comprising a notched wheel fixed to the spindle, a pawl, and spring means for releasably holding the pawl in a notch, the notches comprising radially extending V-shaped grooves on the side of the wheel, the pawl-engaging portion of each notch being approximately symmetrical about an axial plane to render the pawl's resistance to rotation of the wheel approximately equal in each direction, and the notches on one ratchet wheel being in closer spaced relation to each other than are the notches on the other ratchet wheel.

9. An elongate abrasive implement for the application of abrasive tape comprising an outwardly extending blade or finger which forms the forward portion of the implement, a handle which forms the rear portion of the implement, an intermediate shank portion hollowed out to form a supply magazine having suitable apertures through which the tape may leave and re-enter the magazine, the longitudinal axes of the finger, shank and handle being in approximate alignment, the finger having at least one backing surface adjacent to which abrasive tape may be laid to back the tape during an abrading operation, two spindles rotatably mounted within the magazine, means for manual rotation of the spindles separately in either direction, and a braking means associated with each spindle adapted to hold the spindles normally fixed, comprising a notched wheel fixed to the spindle, a pawl, and spring means for releasably holding the pawl in a notch, the pawl and notches being shaped and positioned to unseat the pawl and release the wheel in response to manual pressure in either direction through the wheel-rotating means.

10. The device of claim 9 in which the notches comprise radially extending V-shaped grooves on the side of the wheel.

11. The device of claim 9 in which the notches are in closer spaced relation to each other on one wheel than on the other.

12. The device of claim 9 in which the notches comprise radially extending V-shaped grooves on the side of the wheel, and are in closer spaced relation to each other on one wheel than on the other.
